Primary Examiner — Zenia I Bennett

(57) **CLAIM**

The ornamental design for a hair tie, as shown and described.

DESCRIPTION

FIG. 1 is a front elevational view of a hair tie showing my new design, the back view being a mirror image thereof; FIG. 2 is a front elevational view thereof, with the hair tie bent halfway; and,

FIG. 3 is a front elevational view thereof, with the hair tie closed.

1 Claim, 3 Drawing Sheets

FIG. 1

FIG. 2

FIG. 3
